METHOD FOR RECOVERY OF OIL FROM
WELLSEugene R. Brownscombe, Dallas, Tex., assignor to
The Atlantic Refining Company, Philadelphia,
Pa., a corporation of Pennsylvania

Application April 27, 1950, Serial No. 158,386

5 Claims. (Cl. 166—21)

1

This invention relates to a method for producing oil from a subterranean oil reservoir. More particularly, the invention relates to the recovery of oil from a reservoir by means of normally gaseous hydrocarbons at high pressures.

In the recovery of oil from a subsurface oil reservoir, it has been the practice heretofore to permit the oil to flow from the reservoir under the force of the native reservoir energy which may be in the form of a water, gas cap, or gas drive, or combinations thereof. This production, by virtue of native reservoir energy, is commonly referred to as "primary recovery." Further, it has been common practice to augment the native reservoir energy either during the early stages of oil production or more often after the reservoir has approached its economic production limit by primary recovery methods. This may be accomplished by any one or more of several known methods including gas and water injection to provide artificial pressure drives and production in this manner is termed "secondary recovery." In providing a reservoir with such a gas or water drive it is conventional practice to inject the gas or water into the oil producing zone at relatively low pressures of the order of 1,500 p. s. i. Although these methods of secondary recovery have resulted in an increase in the ultimate recovery of oil over that possible solely by means of primary recovery methods, in some cases only about 20% to 30% of the initial oil in place is recovered and frequently as much as 50% of the oil remains after depletion of the reservoir regardless of the heretofore known method or methods of primary and secondary recovery employed for producing the oil.

In copending United States application, Serial No. 142,568, filed February 6, 1950, now abandoned, by Leonidas P. Whorton and Eugene R. Brownscombe, there is disclosed a method for producing from an oil reservoir whereby a greater amount of oil is recovered than otherwise might be recovered by previously known methods of primary and secondary recovery. In accordance with such method, normally gaseous hydrocarbons are injected into the reservoir at a pressure in excess of 3,000 p. s. i. and are caused to pass therethrough in contact with the oil contained therein to force said oil from the reservoir. Without decreasing substantially the reservoir pressure, oil forced from the reservoir by the injected gas is removed to the surface of the earth.

Although such method is very effective and high recoveries are realized thereby, the application of the method is somewhat restricted by the relatively large volume of normally gaseous hydrocarbons required to practice the same. Thus in areas where large supplies of such gas are not

2

readily available for economic reasons the application of the method is impractical.

The present invention is directed to improvements in the foregoing method whereby the same oil recovery or degree of depletion may be realized by means of relatively small volumes of normally gaseous hydrocarbons. It has been discovered that a greater amount of oil may be recovered from a subterranean oil reservoir than otherwise might be recovered by injecting into the reservoir through an injection well normally gaseous hydrocarbons at a pressure in excess of 3,000 p. s. i. and in an amount substantially less than one, but more than 0.1, hydrocarbon pore volume, thereafter injecting inert fluid, hereinafter defined, into the reservoir through the same well at approximately the same pressure to cause the normally gaseous hydrocarbons to pass through the reservoir in contact with the oil contained therein, simultaneously with said injecting operations maintaining the reservoir pressure at a production well communicating with the reservoir and spaced from the injection well of the same order of magnitude but sufficiently below the injecting pressure so as to permit oil to flow from the reservoir, and removing to the earth's surface through the production well oil swept from the reservoir primarily in the liquid phase. The method of this invention is applicable to virgin reservoirs and also partially depleted reservoirs, provided, however, that the reservoir has not been depleted to the extent that injected gas would bypass the oil and thereby effect recovery merely by evaporation into the injected gas and subsequent recovery from the gas by retrograde condensation at the earth's surface.

This method is to be distinguished from conventional methods of oil production wherein natural gas is injected into the reservoir at relatively low pressures of the order of 1,500 p. s. i. for the purpose of providing a gas drive to augment the natural reservoir pressure. These heretofore known methods of oil production by means of a gas drive differ from the method of the subject invention in that the gas is injected into the reservoir at a pressure much lower than the minimum pressure necessary for carrying out the present invention, and further, in that the gas drive functions merely to sweep oil from the reservoir and does not bring about viscosity and reservoir ratio changes necessary to realize a substantial increase in the recovery of oil over that obtainable in inert gas or water drives, as does the method of the present invention.

Accordingly, one object of this invention is to provide an improved method for producing from an oil reservoir.

Another object is to provide such a method

wherein normally gaseous hydrocarbons in an amount less than one, but more than 0.1, hydrocarbon pore volume, hereinafter defined, are injected into the oil reservoir and thereafter inert fluid is injected thereinto to cause the injected hydrocarbons to pass through the reservoir in contact with the oil, the injection steps being under conditions such that a greater amount of oil is recovered than otherwise might be recovered by conventional methods of primary and secondary recovery.

A further object of this invention is to provide such a method wherein less than one, but more than 0.1, hydrocarbon pore volume of normally gaseous hydrocarbons is injected into the oil reservoir at a pressure in excess of 3,000 p. s. i., thereafter inert fluid at substantially the same pressure is injected thereinto to cause the injected hydrocarbons to flow through the reservoir in contact with the oil contained therein, and oil primarily in the liquid phase swept from the reservoir is removed to the earth's surface.

Other objects and features of the invention will be apparent from the description and drawing which follow.

The drawing is a diagrammatic view showing a system for carrying out the present invention.

Referring to the drawing, numeral 1 denotes generally the surface of the earth. Communicating with oil reservoir 2 are injection well 3 and production well 4 spaced from the injection well. These wells may be of a conventional type and each includes, for example, at least a casing string 5, the interior of which is in communication with reservoir 2 through suitable perforations 6, and a tubing string 7 disposed within the casing for conducting fluids to or from the reservoir.

In accordance with this invention, normally gaseous hydrocarbons, such as gaseous mixtures containing methane with minor amounts of the lower molecular hydrocarbons, are compressed to a desired pressure above 3,000 p. s. i. by a suitable pump or compressor 8, which may be of any conventional type, and are passed through valve controlled pipe 9 into injection well 3 from which the injected gas flows into the reservoir to contact the oil contained therein. Gas from a conventional oil field separator 10, provided for stabilization of production flowing from reservoir 2 to the well surface through production well 4, as described below, may be employed as the injection gas, the separator gas entering compressor 8 through flow pipe 11 and valve controlled line 12. In practice, however, the volume of separator gas frequently is inadequate, making it necessary to supplement it with gas obtained from a suitable external source, not shown, such as a gas well. If desired, the injection gas may consist solely of gas from the external source, which gas is conducted to compressor 8 through valve controlled line 13 and flow pipe 11.

Injection of normally gaseous hydrocarbons is continued until a predetermined volume, ascertained in a manner described below, and which in all cases is substantially less than one, but greater than 0.1, hydrocarbon pore volume has been introduced into the reservoir. At that time injection of normally gaseous hydrocarbons is discontinued and injection of an inert fluid is commenced. The inert fluid is likewise injected into the reservoir at a pressure in excess of 3,000 p. s. i., and preferably at substantially the same pressure as the gaseous hydrocarbons. Inert fluid is used herein to denote a fluid other than hydro-

carbons which has low solubility in the reservoir oil. Included in such term are water, nitrogen, air, and other fluids of low solubility. The inert fluid functions to drive or force the gaseous hydrocarbons through the reservoir in contact with the oil contained therein without decreasing substantially the reservoir pressure.

The inert fluid may be obtained from any convenient source and is introduced into pump or compressor 8 through valve controlled line 13 and flow pipe 11, the valve in line 12 previously having been closed to prevent further introduction of normally gaseous hydrocarbons into the compressor and the valve in pipe 14 having been opened to permit gas to pass from separator 10.

Simultaneously with the injection of gaseous hydrocarbons and inert fluid, the reservoir at production well 4 is maintained at a pressure of the same order of magnitude as at the injection well 3 but sufficiently below the injecting pressure so as to permit oil to flow through the reservoir.

The oil caused to flow through the reservoir by the injected gas is removed to the surface of the earth through production well 4.

Most of the oil recovered by this method is in the liquid phase but a small amount flows to the well as a dense vapor phase. In some cases, at pressures in excess of 4,000 p. s. i. the effluent, which is initially a liquid and ultimately a gas, flows from the reservoir into the well as a single phase throughout the entire operation.

Injection of inert fluid is continued until oil and normally gaseous hydrocarbons no longer flow from the reservoir in substantial quantities and injected inert fluid begins to be produced through well 4. At that time recovery of oil in accordance with the present invention is completed.

The oil produced through well 4 flows by means of valve controlled pipe 15 into separator 10, operated at a pressure of 500 p. s. i., for example, less than the pressure of the oil at the well head, wherein the oil is stabilized. As pointed out hereinabove, the separator gas, which comprises normally gaseous hydrocarbons, may be conducted by means of flow line 12 into compressor 8 for injection into the reservoir through well 3. However, after injection of gaseous hydrocarbons is discontinued and injection of inert fluid is commenced, as above described, the valve in line 12 is closed and the valve in pipe 14 is opened to permit the overhead gases to pass from the separator. The stabilized oil from separator 10 flows through valve controlled pipe 16 into a second separator 17, which preferably is operated at atmospheric pressure, wherein the oil is stabilized at such pressure. The overhead gas passing through pipe 18 preferably is employed as fuel for the operation of auxiliary field equipment. The stabilized oil is passed from separator 17 into a suitable storage tank 19 by means of valve controlled flow line 20.

It has been discovered that with substantially less than one hydrocarbon pore volume of normally gaseous hydrocarbons there may be recovered from a reservoir a greater amount of oil than otherwise might be recovered with conventional methods of primary and secondary recovery, by injecting into the reservoir at a pressure in excess of 3,000 p. s. i. a predetermined volume of such gas, followed by inert fluid which functions to cause the hydrocarbon gas to pass through the reservoir in contact with the oil contained therein while maintaining the pressure in the reservoir. This increased recovery is be-

Inert
fluids

lieved to be due to changes in the viscosity of the reservoir oil and injected hydrocarbon gas and also to the high miscibility of the oil and gas when brought into contact in the reservoir at pressures in excess of 3,000 p. s. i. As the injected normally gaseous hydrocarbons contact the liquid some of the oil evaporates into the gas and simultaneously some of the gas dissolves in the oil whereby the viscosities of the fluids approach one another. As the viscosities of the two fluids become more nearly equal the oil production approaches the condition of displacement of a fluid by fluid of the same composition which would result in complete displacement of the fluid originally in place. It is to be understood, however, that the invention is not limited by any specific theory of operation and that any theory that has been advanced is merely to facilitate the disclosure of the invention.

By hydrocarbon pore volume, as used herein, is meant the volume occupied by reservoir oil in that portion of the reservoir through which the injected normally gaseous hydrocarbons pass in flowing from the injection well 3 to the production well 4. For example, in the case of a small reservoir having substantially no channels through which the injected gas may be bypassed through only a small portion of the reservoir and with the injection well and production well communicating with the reservoir at opposite sides thereof, the hydrocarbon pore volume is equal substantially to the volume of the reservoir occupied by all of the oil. In cases where the reservoir is relatively large and the injection and production wells are located at one end of the reservoir the hydrocarbon pore volume is that volume of the reservoir occupied by the reservoir oil through which the injected normally gaseous hydrocarbons actually pass in moving from the injection well 3 to the production well 4. The hydrocarbon pore volume may be determined sufficiently close for the purpose of this invention in accordance with procedures well known in the industry from certain information obtained by established investigating methods. Such procedures are so well known in the art that a description thereof is unnecessary.

As above mentioned, prior to injection of the inert fluid there is introduced into the reservoir a predetermined volume of normally gaseous hydrocarbons, which is less than one, but greater than 0.1, hydrocarbon pore volume. Such volume may be ascertained by laboratory experiments, below described, on a core under conditions simulating recovery of oil from a subterranean oil reservoir. The core may comprise either a synthetic core formed of sand or other suitable material, such, for example, as carborundum, or a core-sample obtained from the reservoir by conventional coring methods.

The following laboratory experiments exemplify a method and apparatus for determining the volume of normally gaseous hydrocarbons which must be injected into the reservoir before injection of inert fluid for recovering oil in accordance with the present invention.

With information concerning the characteristics, including relative permeability, which may be determined by any of several well known methods, of the reservoir from which it is desired to produce oil, an artificial core is prepared by placing in a 25-foot length of 2-inch metal tubing, having insulated heating coils provided around the same, a consolidated core sample which may be composed of several segments and

which has characteristics approaching those of the subterranean reservoir. The segments preferably are joined by flat, narrow rings, the whole of the core sample being sealed within a rubber sheath by applying sufficient fluid pressure in the annulus between the sheath and metal tubing thereby reducing to a minimum channelling along the surface of the core sample. A 26 liter pressure vessel used for storing the reservoir oil to be displaced is connected by means of a pipe to one end of the artificial reservoir and a suitable pump is connected in the pipe for transferring to the reservoir high pressure fluids. The normally gaseous hydrocarbons to be injected into the simulated reservoir are stored in a high pressure vessel having a capacity of about 30 liters and which preferably is connected by a suitable line to the same end of the reservoir as is the 26 liter storage cell hereinbefore mentioned. To the other end of the simulated reservoir a single pipe is connected for conducting effluent from the reservoir to a high pressure visual separator which is of any conventional design. The function of the visual separator is to permit observation of the reservoir effluent whereby a determination may be made, if desired, of whether the effluent flowing from the reservoir at any instant is a liquid or gas or a mixture thereof. From the visual separator the reservoir effluent is conducted by means of a valve controlled pipe into a second separator operated at atmospheric pressure wherein the effluent is stabilized. The stabilized liquid and the gaseous fraction from the atmospheric separator are metered to determine the volume thereof. The two fractions are analyzed periodically to determine the compositions thereof from which the number of hydrocarbon pore volumes of injected gas in the effluent may be determined, knowing the compositions of the injected gas and original reservoir oil.

The laboratory experiments with the above described apparatus are conducted in the following manner. Oil which has been stabilized at atmospheric pressure, and which is referred to herein-after as "dead" oil, is pumped into the simulated core or reservoir under a pressure of 500 p. s. i., for example, to displace air or gas or other fluid which might be present. By means of the heating coil the core is brought up to the desired reservoir temperature. The reservoir oil is then pumped into the core from the 26 liter storage vessel until all of the dead oil has been displaced and the core is at the desired reservoir pressure, such as 4,000 p. s. i. for example, the amount of dead oil displaced being equal to one hydrocarbon pore volume. At this time injection of normally gaseous hydrocarbons is commenced by displacement of such gas from the 30 liter vessel with water. As pointed out hereinabove, the gas is injected at a pressure in excess of 3,000 p. s. i. By maintaining the effluent end of the core at a pressure somewhat lower than the injection pressure, such, for example, about 50 p. s. i. lower, the injected gas is caused to flow through the core forcing oil therefrom. The oil passes through the visual separator and into the atmospheric separator wherein it is stabilized. Gas injection is continued until the gas-oil ratio of the effluent is equal to 30,000. The effluent is measured and analyzed and the number of hydrocarbon pore volumes of injected gas is calculated, knowing the compositions of the injected gas and original reservoir oil. Normally gaseous hydrocarbons having a volume substantially equal to the calculated number of hydrocarbon pore

volumes of the subterranean reservoir must be injected into such reservoir in order to recover oil therefrom in accordance with this invention.

The following examples of results obtained in the laboratory on an artificial reservoir by experiments conducted as above described, illustrate the quantity of normally gaseous hydrocarbons required to be injected into and forced by inert gas through a subterranean reservoir, having characteristics similar to the artificial reservoir employed, to recover oil in accordance with this invention.

Example I

Employing injection gas and reservoir oil of the following compositions, at an injection pressure of 4,000 p. s. i. and with the reservoir at 140° F. a recovery of 88% of the original oil in place was realized utilizing 1.31 hydrocarbon pore volumes of injected gas. However, only 0.43 hydrocarbon pore volume was produced and appeared in the effluent, this amount of injection gas being all that is necessary to effect the recovery. Thus, normally gaseous hydrocarbons of the same composition and in an amount equal to 0.43 hydrocarbon pore volume of the subterranean reservoir are required to produce oil of the same composition from such reservoir under similar conditions of temperature and pressure, in accordance with this invention.

	Composition of Injected Gas, Mol Percent	Composition of Reservoir Oil, Mol Percent
C ₁	72.41	44.60
C ₂	16.33	12.70
C ₃	8.01	9.60
C ₄	2.24	6.50
C ₅	0.58	3.10
C ₆	0.10	3.65
C ₇ (Av. Mol. Wt. 200)	0.33	19.85
Total	100.00	100.00

Example II

Employing injection gas and reservoir oil of the following compositions, the reservoir oil being of the same composition as that employed in Example I, at the same injection pressure and reservoir temperature, a recovery of 80% of the original oil in place was realized utilizing 1.00 hydrocarbon pore volume of injected gas. However, only 0.20 hydrocarbon pore volume was produced and appeared in the effluent, this amount of injection gas being all that was necessary to effect the recovery. Thus, normally gaseous hydrocarbons in an amount equal to 0.20 hydrocarbon pore volume of the subterranean reservoir are required to produce oil of the same composition from a subterranean reservoir having characteristics similar to the artificial reservoir and under the same conditions of temperature and pressure, in accordance with the invention.

	Composition of Injected Gas, Mol Percent	Composition of Reservoir Oil, Mol Percent
C ₁	86.0	44.60
C ₂	14.0	12.70
C ₃		9.60
C ₄		6.50
C ₅		3.10
C ₆		3.65
C ₇ (Av. Mol. Wt. 200)		19.85
Total	100.0	100.0

By comparison of the two examples it will be observed that the composition of injected gas affects not only the recovery but also the injection gas requirements. Whereas economics might dictate use of lean gas, such as a mixture of methane and ethane with a small amount of heavier hydrocarbons for injection into the reservoir, nevertheless it is possible to bring about a further increased recovery by use of a rich gas, i. e., a normally gaseous hydrocarbon mixture containing a substantial amount of propane and butane and heavier hydrocarbons. Similarly, a greater recovery may be realized at injection pressures of 6,000 p. s. i. and higher than at 3,500 p. s. i., but because of the relatively high costs involved in repressuring gas it may be preferred to inject the gas at about 4,000 p. s. i.

An alternate method for determining the volume of normally gaseous hydrocarbons which must be injected into the reservoir before injection of inert fluid for recovering oil in accordance with the present invention, and which is preferred in cases where water is to be employed as the inert fluid, contemplates use of the same apparatus as the above method and is substantially the same as the latter except that a given amount of normally gaseous hydrocarbons, such, for example, as 0.1 hydrocarbon pore volume, is injected into the artificial reservoir and thereafter inert fluid is injected therewith until the gas-oil ratio of the effluent is equal to 30,000 where the inert fluid is a gas or until water in substantial quantities appears in the effluent where the inert fluid is water. The oil recovery is then determined. The foregoing procedure is repeated several times using progressively larger volumes of normally gaseous hydrocarbons. When the recoveries are plotted as a function of the quantity of normally gaseous hydrocarbons employed it will be noted that the recovery gradually increases with increase in quantity of injected normally gaseous hydrocarbons up to a certain fraction of a hydrocarbon pore volume and thereafter remains substantially constant. This is the amount of normally gaseous hydrocarbons which must be injected into a reservoir in order to recover oil therefrom in accordance with the present invention.

This invention, as above mentioned, contemplates the injection, into the reservoir at a pressure in excess of 3,000 p. s. i., of normally gaseous hydrocarbons in an amount less than one, and greater than 0.1, hydrocarbon pore volume. The quantity of hydrocarbon gas required is influenced by various factors such, for example, as compositions of injection gas and reservoir oil, injection pressure, and the composition of inert fluid. The volume required, however, is determined, as above described by laboratory experiments on an artificial reservoir.

While in the foregoing there has been shown and described the preferred embodiment of this invention, it is to be understood that minor changes in the details of construction, combination, and arrangement of parts may be resorted to without departing from the spirit and scope of the invention as claimed. For example, whereas only a single injection and production well are shown, two or more of such wells may be utilized if desired.

I claim:

1. A method for recovering oil from a subterranean oil reservoir containing oil in quantities such that gas injected therewith will not substantially bypass the oil, and in communication

with which are an injection well and a production well spaced from the injection well, comprising the steps of injecting into the reservoir through the injection well normally gaseous hydrocarbons at a pressure between about 3,000 p. s. i. and 6,000 p. s. i. and in an amount substantially less than one hydrocarbon pore volume, thereafter injecting inert fluid into the reservoir through the injection well at a pressure between about 3,000 p. s. i. and 6,000 p. s. i. to cause the normally gaseous hydrocarbons to pass through the reservoir in contact with the oil contained therein, simultaneously with the injecting steps maintaining the reservoir pressure at the production well substantially of the same order of magnitude but sufficiently below the injecting pressure so as to permit oil to flow from the reservoir, and removing to the earth's surface through the production well oil swept from the reservoir substantially free from any separate gas phase.

2. A method for recovering oil from a subterranean oil reservoir containing oil in quantities such that gas injected therewith will not substantially bypass the oil, and in communication with which are an injection well and a production well spaced from the injection well, comprising the steps of injecting into the reservoir through the injection well normally gaseous hydrocarbons at a pressure between about 3,000 p. s. i. and 6,000 p. s. i. and in an amount substantially less than one, but more than 0.1, hydrocarbon pore volume, thereafter injecting inert fluid into the reservoir through the injection well at a pressure between about 3,000 p. s. i. and 6,000 p. s. i. to cause the normally gaseous hydrocarbons to pass through the reservoir in contact with the oil contained therein, simultaneously with the injecting steps maintaining the reservoir pressure at the production well substantially of the same order of magnitude but sufficiently below the injecting pressure so as to permit oil to flow from the reservoir, and removing to the earth's surface through the production well oil swept from the reservoir substantially free from any separate gas phase.

3. A method for recovering oil from a subterranean oil reservoir containing oil in quantities such that gas injected therewith will not substantially bypass the oil, and in communication with which are an injection well and a production well spaced from the injection well, comprising the steps of injecting into the reservoir through the injection well normally gaseous hydrocarbons at a pressure between about 3,000 p. s. i. and 6,000 p. s. i. and in an amount substantially less than one, but more than 0.1, hydrocarbon pore volume, thereafter injecting water into the reservoir through the injection well at a pressure between about 3,000 p. s. i. and 6,000 p. s. i. to cause the normally gaseous hydrocarbons to pass through the reservoir in contact with the oil contained therein, simultaneously with the injecting steps maintaining the reservoir pressure at the production well substantially of the same order of magnitude but sufficiently below the injecting pressure so as to permit oil to flow from the reservoir, and removing to the earth's sur-

face through the production well oil swept from the reservoir substantially free from any separate gas phase.

4. A method for recovering oil from a subterranean oil reservoir containing oil in quantities such that gas injected therewith will not substantially bypass the oil, and in communication with which are an injection well and a production well spaced from the injection well, comprising the steps of injecting into the reservoir through the injection well normally gaseous hydrocarbons at a pressure between about 3,000 p. s. i. and 6,000 p. s. i. and in an amount substantially less than one, but more than 0.1, hydrocarbon pore volume, thereafter injecting nitrogen into the reservoir through the injection well at a pressure between about 3,000 p. s. i. and 6,000 p. s. i. to cause the normally gaseous hydrocarbons to pass through the reservoir in contact with the oil contained therein, simultaneously with the injecting steps maintaining the reservoir pressure at the production well substantially of the same order of magnitude but sufficiently below the injecting pressure so as to permit oil to flow from the reservoir, and removing to the earth's surface through the production well oil swept from the reservoir substantially free from any separate gas phase.

5. A method for recovering oil from a subterranean oil reservoir containing oil in quantities such that gas injected therewith will not substantially bypass the oil, and in communication with which are an injection well and a production well spaced from the injection well, comprising the steps of injecting into the reservoir through the injection well normally gaseous hydrocarbons at a pressure between about 3,000 p. s. i. and 6,000 p. s. i. and in an amount substantially less than one, but more than 0.1, hydrocarbon pore volume, thereafter injecting air into the reservoir through the injection well at a pressure between about 3,000 p. s. i. and 6,000 p. s. i. to cause the normally gaseous hydrocarbons to pass through the reservoir in contact with the oil contained therein, simultaneously with the injecting steps maintaining the reservoir pressure at the production well substantially of the same order of magnitude but sufficiently below the injecting pressure so as to permit oil to flow from the reservoir, and removing to the earth's surface through the production well oil swept from the reservoir substantially free from any separate gas phase.
